DESIGN FOR COVER PAPER OR SIMILAR ARTICLE

Reed M. Grunden, Sandusky, Ohio, assignor to
The Hinde and Dauch Paper Company, Sandusky, Ohio, a corporation of Ohio

Application December 5, 1935, Serial No. 59,920

Term of patent 7 years

To all whom it may concern:

Be it known that I, Reed M. Grunden, a citizen of the United States and a resident of Sandusky, county of Erie, and State of Ohio, have invented a new, original, and ornamental Design for Cover Paper or Similar Article, of which the following is a specification, reference being had to the accompanying drawing, forming a part thereof.

In the accompanying drawing the figure is a face view of a portion of cover paper or similar article showing my new design.

The dominant feature of this design consists in a plurality of peaked trees with a common base and having a uniform color intensity. This feature occurs in units such as indicated by the dot-and-dash lines A—B—C—D.

What I claim is:

The ornamental design for cover paper or similar article as shown and described.

Signed by me this 2nd day of December, 1935.

REED M. GRUNDEN.
